UNITED STATES PATENT OFFICE.

FRANK ADAMAC, OF LAURELTON, NEW YORK, ASSIGNOR TO RUDOLPH FELIX, DOING BUSINESS AS THE OVALITE COMPANY.

DESIGN FOR A LIGHTING-FIXTURE BRACKET.

Application filed December 23, 1924. Serial No. 11,776. Term of patent 7 years.

To all whom it may concern:

Be it known that I, FRANK ADAMAC, a citizen of the United States, and a resident of Laurelton, county of Queens, and State of New York, have invented a new, original, and ornamental Design for Lighting-Fixture Brackets, of which the following is a specification, reference being had to the accompanying drawing, forming a part hereof.

In these drawings:

Fig. 1 is an elevational view of the light-

ing fixture bracket, the portion indicated in full line outline being ornamented in the same manner as the portion more fully illustrated.

Fig. 2 is a side elevation of the lighting fixture bracket.

I claim:

The ornamental design for a lighting fixture bracket substantially as shown and described.

FRANK ADAMAC.
